TWO-PART ELECTRICAL CONNECTOR

Marnie Carlton Averitt, Timonium, Md., assignor to
AMP Incorporated, Harrisburg, Pa.

Filed Nov. 23, 1971, Ser. No. 201,609

Term of patent 14 years

Int. Cl. D13—03

U.S. Cl. D26—1 A

FIG. 1 is a perspective view of a two-part electrical connector in accordance with the invention,

FIG. 2 is a side view, the two parts being disengaged from, and in alignment with, each other in this view.

The broken line disclosure of conductors is for illustrative purposes only.

The two sides of the connector are identical so that the opposite side from the side shown in FIG. 2 has the same appearance as the side shown in FIG. 2.

I claim:

The ornamental design for a two-part electrical connector, as shown and described.
